LUMINOUS TUBE

Raymond Nauth, Buffalo, N. Y., assignor, by
mesne assignments, to Flexlume Corporation,
a corporation of New York

Application January 8, 1935, Serial No. 862

9 Claims. (Cl. 176—122)

This invention relates to luminous or glow tubes suitable for advertising purposes, and it has particular reference to a durable and permanent tube which is stable and operative at low atmospheric 5 temperatures.

When a small quantity of gas at a low pressure is enclosed in a glass tube and subjected to the influence of a high potential electric discharge passing therethrough, a luminous glow in the gas 10 is produced. This effect is usually attributed to the bombardment of the gaseous molecules by electrons emanating from the cathode, with a resulting ionization of the gas, and its corresponding phenomenon of luminescence. The color produced is more or less specific for the gas so ionized,—thus, neon invariably produces a red color, while argon, or mixtures of argon and neon, produce a blue. If a small quantity of mercury vapor be included in the tube, the blue color is 15 more pronounced.

While a blue color may be obtained by electronic ionization of argon, a number of difficulties are encountered in utilizing this effect in a practical way. Some are due to the high ionizing potential of argon, in comparison with other gases, such 20 as neon. The higher the potential, the greater the prospects of cathodic disintegration, which leads to the early failure of the tube. If, as just suggested, mercury be included in the system (to provide a certain quantum of ions for secondary ionization of the argon or other gas), there is a strong possibility of amalgamation between mercury and the cathode; which effect 25 again increases the potential drop.

One particular deleterious effect arising from mercury addition, in a haphazard manner, to a low pressure gas tube, is that of "fading", or the failure of the tube at low temperatures. What has been suggested in the preceding paragraphs applies to operation at normal atmospheric 30 temperatures, such as those obtaining in the summer months in the north temperature zone. When, however, winter temperatures prevail, such as from say plus fifteen to minus thirty degrees 35 Fahrenheit, the glow light which might otherwise obtain cannot be produced, or, if instituted, it diminishes in brilliance, and ultimately goes out altogether. Or, in a glow tube containing no mercury, there is the possibility of failure at low 40 temperatures, due to the low temperature of the tube wall, rendering it more capable of adsorbing the contained gas. This is the effect which is herein denominated as "fading".

Critical study of the ultimate cause of fading, 45 or its underlying philosophical explanation, in-

volves further considerations of molecular and atomic physics which are too abstruse for detailed presentation here,—it being the primary purpose of this specification to describe useful ways in which the effect may be circumvented. Suffice it 5 to say, therefore, that such explanation may proceed on some one or more of these premises. (1) That by virtue of the high temperature gradient between the electrode and the exterior wall of the glow tube, which exists at winter temperatures, the mercury ions are discharged before they can enter the electron stream in sufficient quantity to produce any useful result, with the consequent raising of the potential drop through the 10 gas to an unattainable value. (2) That vaporization of the mercury is confined to the electrode region, and such mercury attacks the electrode with the formation of a high boiling point surface amalgam, attractive to vaporized atomic mercury, which in turn increases the potential drop. 15 (3) That such mercury as is vaporized by the heat of the electrode forms a shield therearound, in which only a small percentage of the atoms or molecules are in an ionized state, thus locally 20 exhausting the electron discharge from the cathode before it can appreciably affect the gaseous medium. 25

Whatever may be the soundness or acceptability of the foregoing or other views is, of course, a matter of opinion, but the fact on which the 30 foregoing hypotheses are based, namely, that tubes "fade" with reduction of temperature, is demonstrable by simple experiment.

With these general considerations in mind, 35 it may be stated that the present invention contemplates improvements in luminous tubes, to the end that the light produced therein shall be of good color, and permanent at normal and low temperatures, and such tubes shall have a long life.

These general objects may be achieved by the 40 conjoint or separate use of the hereinafter described expediences. According to one of them, it is proposed to contain mercury in a small still which may be provided with a reflux condenser, 45 and which is heated by the electrode to provide an aliquot, but not excessive, quantity of mercury vapor to augment the desired operation.

According to another phase of the invention, 50 it is proposed to protect the electrode from excess amounts of mercury, so that amalgamation will not take place.

Viewed from a different aspect, the invention 55 contemplates the association with the electrode and ionized gas of the heavy isotopes of mer-

cury, in which, as it has been determined, there are certain spectral and other properties advantageous in tubes of the type herein described.

In still another aspect, the invention proposes, 5 in lieu of ordinary mercury or the stated isotopic concentrations, or in combination therewith, the use of low boiling point amalgams, such as may be made with the elements gallium and indium.

And in another phase, the invention proposes 10 an oxidized metal electrode having thereon a surface coating of or derived from a salt such as ruthenium chloride.

A typical form of electrode and tube assembly 15 embodying the principles of the invention is illustrated in the drawing, in which Fig. 1 is a longitudinal section and Fig. 2 is a transverse section.

The numeral 10 designates what may be termed 20 the end of the visible or glow portion of the luminous tube, which, as it is here supposed for exemplary purposes, is of considerable length and takes the form of one or more letters or symbols used for advertising purposes. To the end, or other point, but preferably a low point, of the 25 visible tube 10 is affixed an electrode tube portion or case 11, of slightly greater diameter, the purpose of which is to receive an electrode and to seal off the visible tube so that gas contained therein cannot escape. Disposed within the electrode 30 portion 11 is another tube 13, also of glass, which may be termed the electrode sheath, and containing a suitable electrode 14. As herein illustrated, the electrode 14 is in the form of a coiled cylinder, of a nature hereinafter described, 35 but it will be understood that other forms of electrodes may be used.

A lead wire 15, secured to the electrode 14, 40 extends through the sheath 13 and electrode portion 11, to provide a means for connecting the usual electric circuit to the tube. The glass tube 13 is flattened down and blocked in the rear of the mesh 14, as indicated by the numeral 45 16, and tube 11 has its end turned over and integrated with the blocked end of the tube 13, as indicated by the numeral 17, thereby sealing the tubes from leakage.

The forward end of the sheath 13 is drawn 50 down to provide a relatively small aperture 21, thus forming a type of guide through which the electrons must flow, and a restriction resisting 55 the counter-flow of excess quantities of material contained in the remaining portions of the entire tube. The walls of the aperture 21 are then flared downwardly with a reverse bend 60 to a point adjacent the wall of the tube 11, thus forming an annular pocket 22, which may be further defined by drawing the glass inward, as indicated by the numeral 23, and then outward to form a joint with the tube 11, adjacent its junction with the tube 10.

The pocket 22 is filled with as much clean mercury as it will comfortably hold, and by the term "mercury", when used generically, it is meant to embrace not only the element commonly 65 regarded as mercury, but also such amalgams or isotopic concentrates as are useful in the same relationship. When the sign is formed to include the foregoing principles, it is then evacuated and filled with a suitable quantity of inert 70 gas. For the purpose of producing a blue light, argon may be used, or mixtures of argon and neon, or other suitable mixtures.

It will be observed that when current is applied to the electrodes, the generated heat is 75 concentrated at the pocket 22, thereby forming

a still for the contained mercury. Hence, whatever the external temperature may be, the mercury will be caused to vaporize, and the parts should be so proportioned, for best operation, as to produce such vaporization at the lowest temperatures to which the sign is apt to be subjected. 5

At the same time, however, it is not advantageous to distill the mercury at such rate as to exhaust the still, or to eject the vapors entirely 10 into the visible portion 10 of the tube. Therefore, the flared portion 23 is included, with a relatively large radiating surface, to provide a reflux condenser for a major portion of the vapors, thereby not only protecting the visible 15 portion 10, but also insuring the presence of some mercury in the pocket 22, since the condensate flows back into the still. It will thus be seen that the present invention provides for the production of, or what might be termed the "priming" 20 of the sign with, mercury vapors, a part of which are in the ionic state, regardless of atmospheric temperatures. On the basis of the theory that such ions facilitate the conduction 25 of the current, it follows that the sign may be operated from a normal electric potential without regard to the existing atmospheric temperatures.

Having thus described means for insuring the institution of the luminous glow, attention is now 30 invited to a further consideration of the mode of protecting the electrode 14 from excesses of mercury vapor. As stated in the forepart of this specification, it is well known that electrodes are subject to the phenomenon known as disintegration, 35 which, generally speaking, means that particles of the electrode actually depart from the solid mass. Such disintegration alters the electrode surface, and tends to induce gas adsorption and occlusion, all of which effects increase the potential drop, and so lead to operating failure for an 40 initially satisfactory voltage. It has also been reported in the literature that sodium amalgam, when used as an electrode, disintegrates to such an extent as to coat the walls of the visible tube 45 portion with a substance rapidly adsorbing the contained gas. From these considerations, as well as others, and from practical observations, it appears that if too much mercury is allowed to 50 contact the electrode, even if it be of some reputedly non-amalgamating substance such as iron, the electrode material is damaged and inefficient 55 operation results.

At the same time, as I have discovered, it is 60 advantageous to admit a limited quantity of mercury vapor to the cathode, and the line of demarcation between too much vapor, and a suitable quantity, as I have determined it for practical purposes, is that which distinguishes from deposition of mercury, and its immediate re-boiling or ionization. I may here suggest, in an endeavor 65 to explain, rather than to limit my invention, that the observation made heretofore by others, to the effect that secondary ionization with mercury is highly inefficient, may be because such observation was made under conditions permitting an excess of mercury to contact the electrode. Therefore, what is desired by the present invention, in this phase, is to limit the quantum of mercury 70 coming into contact with the electrode to that value which can either be readily ionized by the available current, or immediately redistilled by the available heat.

Referring again to the drawing, it will be seen 75

that any mercury coming into contact with the electrode 14 must pass through the small aperture 21, and, in so doing, it is subjected to the full intensity of the electrons flowing from the electrode. While a certain quantity of vapors will so pass the aperture 21, the total quantum is relatively small, and insufficient to form an adherent deposit on the cathode. My experience with the invention further indicates that the ionized mercury is incapable of dislodging particles from the electrode. Hence, while some secondary ionization is obtained, thereby facilitating the conduction of current through the gas, there is small likelihood of the formation of a surface film or amalgam of mercury with the electrode material. In practice, it will be found advantageous to space the sheath 13 from the electrode 14, and to dimension the aperture 21, in such manner that the maximum amount of mercury may surround the electrode in a highly vaporized form, without concurrently forming any adherent deposit.

If a concentrate of the heavier isotopes of mercury be employed, in lieu of the ordinary mercury of the chemists, the foregoing effects are not only obtained to better advantage, but the intensity of blue light is also appreciably increased. With regard to isotopes, it is believed sufficient here to recall that mercury, which has an assigned atomic weight of 200.6, is assumed to be composed of a mixture of chemically indistinguishable atoms, whose several atomic weights lie in the range of 197 to 204. The atoms so mixed together can be separated or concentrated after a fashion into two portions, a light portion containing a higher percentage of the atoms in the range 197 to 200, and a heavy portion containing a higher concentrate of the atoms having weights of 202 to 204. While any desired method may be employed for effecting such concentration, as outlined or referred to by Aston in his work, "Isotopes", 2nd ed., 1924, I have found it sufficient for the purposes here intended to distill a large quantity, of say five kilograms, at the critical boiling point of ordinary pure mercury referred to normal barometric pressure. The vaporization proceeds slowly, and the temperature should be held as close to the established value as possible, until the original mass is concentrated to about 20 grams. While such method is theoretically inefficient, I find it best for economic reasons, since more theoretically efficient methods are too expensive for commercial work.

Analysis of the residue shows that it contains more than a normal amount of the heavier isotopes of mercury, which, either through their greater ionizing ability, or the greater intensity of their emitted blue wave lengths, impart to the glow a durable blue color of greater depth than that obtained with ordinary mercury. Another desirable feature of such concentrate is its passivity toward oxidized metal electrodes.

When ordinary mercury is employed, for example, against an electrode of oxidized nickel, there is a tendency towards too rapid disintegration. The heavy isotopic concentrate, however, may be used with oxidized metal electrodes which are not protected with any further coating, thereby permitting economies in tube construction which otherwise could not be tolerated.

Another form of mercury which may be used is an amalgam with such metals as gallium and indium. These light metals form with mercury low boiling point amalgams, which are readily vaporized by the heat of the electrode. Unlike

sodium amalgam electrodes, however, they do not coat the visible tube walls, or adsorb the contained gas. Hence, the use of these low boiling point amalgams protects the electrode from any tendency to disintegrate by contact with mercury. 5 If the amalgam is prepared with the heavy isotope concentrate, then the advantages of such isotopes may also be concurrently obtained.

As hereinabove stated, the electrodes may be of any suitable form and composition, even oxide 10 coated electrodes being serviceable when used under suitable precautions. For very good results, in conjunction with the foregoing proposals, or for use in ordinary tubes, however, I have found that an electrode may be made according 15 to the following plan. A coil of metal, such as steel containing chromium, is cleaned and is given a surface oxide coating by passing it through an oxidizing flame, or by heating in air to a coloring temperature. The coating so formed should not 20 be so heavy as to flake or scale off, however. After heating, the metal is quenched in a solution of ruthenium chloride, removed, and dried. As a result of this treatment, there is formed on the electrode a firm coating of the ruthenium salt, 25 and the electrode is conditioned for use in luminous tubes.

In the device illustrated in the drawing, it may therefore be supposed that the electrode 14 is provided with a ruthenium coating, and the material marked Hg, in the still 22, is an amalgam containing a concentrate of the heavy isotopes of mercury, thus utilizing all of the foregoing features in combination, to produce a luminous tube of good brilliance under all weather conditions, having a deep blue spectrum, and in which relatively low voltages may be employed. Or, it may be supposed that some of the foregoing features are not utilized, but others are, as it will be readily understood that marked 30 advantages may be obtained by using the various apparent sub-combinations. It will therefore be understood that the scope of the invention should be ascertained in the light of the following 35 claims.

I claim:

1. A luminous tube comprising a visible tube portion and electrode portions affixed thereto and in communication therewith, one of said electrode portions containing an electrode, a glass sheath around said electrode, said sheath being formed with a restricted aperture at its end adjacent said visible tube, said apertured portion merging into a pocket portion and an outwardly flared portion, said pocket portion containing mercury, and said visible tube portion containing an ionized inert gas at a low pressure.

2. A luminous tube comprising a length of visible tubing, electrode portions affixed to and in communication with said length, one of said electrode portions containing an electrode, a glass sheath for said electrode, said sheath being secured to said electrode portion at one end and being drawn down to provide a restricted aperture at the opposite end of said electrode, said tubing being formed with a pocket adapted to receive mercury beyond said restricted portion and being outwardly flared into contact with said electrode portion beyond said pocket portion, said visible tube length containing a gas at low pressure which when ionized under suitable potential produces a blue light.

3. The method of preventing fading in glow tubes which comprises subjecting an isolated inert gas at low pressure to an electric discharge 75

- between a pair of electrodes, and simultaneously subjecting the electrodes and gas to the influence of a limited quantity of mercury vapor distilled by the heat of said electrodes.
5. 4. A luminous tube comprising a visible tube portion and an electrode portion affixed thereto and in communication therewith, said electrode portion containing an electrode, inert gas in said tube adapted to be ionized by an electron discharge from said electrode, and a concentrate of the heavier isotopes of mercury in said tube and adapted to be vaporized therein.
5. A luminous tube comprising a visible tube portion and electrode portions affixed thereto and in communication therewith, said electrode portions containing electrodes for the discharge of a high electric potential through said gas, and a quantity of mercury in said tube adapted to be vaporized during such discharge, said mercury being in the form of an amalgam with a metal of the class composed of gallium and indium.
6. A luminous tube comprising a visible tube portion and electrode portions affixed thereto and in communication therewith, said electrode portions containing electrodes for the discharge of a high electric potential through said visible tube portion, and inert gas in said tube adapted to be ionized by said discharge, a quantity of mercury in said tube adapted to be vaporized by the heat of said discharge, said mercury containing a concentrate of its heavy isotopes, at least one of said electrodes consisting of a metal having a surface coating of its own oxide thereon.
7. In a luminous sign having a visible tube portion and an electrode portion, an electrode in said electrode portion, said electrode being formed of metal having a coating of a ruthenium compound thereon.
8. A luminous sign having a visible tube portion and electrode portions affixed thereto and in communication therewith, one of said electrode portions containing an electrode, said electrode being formed of metal having a coating of a ruthenium compound thereon, an inert gas in said tube portion, and a quantity of mercury in said sign adapted to be vaporized by the heat of said electrode.
9. A luminous sign having a visible tube portion and electrode portions affixed thereto and in communication therewith, one of said electrode portions containing an electrode, said electrode being formed of metal having a coating of a ruthenium compound thereon, an inert gas in said tube portion, and a quantity of mercury in said sign adapted to be vaporized in said tube, said mercury containing a high percentage of the heavy isotopes thereof.

RAYMOND NAUTH. 30
